UNITED STATES PATENT OFFICE.

JESSE P. WILLIAMS, OF BROOKLYN, NEW YORK.

STEAM-RADIATOR.

1,161,567.

Specification of Letters Patent. Patented Nov. 23, 1915.

Application filed April 2, 1914. Serial No. 829,049.

To all whom it may concern:

Be it known that I, JESSE P. WILLIAMS, a citizen of the United States, residing at Brooklyn, in the county of Kings and State 5 of New York, have invented certain new and useful Improvements in Steam-Radiators; and I do declare the following to be a full, clear, and exact description of the invention, such as will enable others skilled in the art 10 to which it appertains to make and use the same.

My invention relates to improvements in steam radiators and analogous forms of vapor heating systems employing flow and 15 return pipes.

The primary object of the invention is to provide extremely simple and efficient means whereby any air within the system may be freed.

20 In carrying out the above end in connection with a radiator, I provide a transverse partition which obstructs communication between a portion of the flow and return pipes and a water trap which establishes communication between the two, the trap serving to allow water of condensation to return to the boiler and preventing any air from returning with said water. For the purpose 25 of allowing this air to escape, I provide the return pipe with a vent adjacent the partition.

A secondary object of the invention is to construct portions of the radiator in such a manner as to provide an air pocket from 35 which the vent discharges and to so position the partition as to cause it to most successfully perform its functions.

With the above and other minor objects in view, the invention resides in certain 40 novel features of construction and combination of parts hereinafter more fully described and claimed and shown in the drawings wherein:—

Figure 1 is a vertical longitudinal section 45 through the center of my improved radiator; Fig. 2 is an end view thereof; and Fig. 3 is a detail horizontal section taken upon the line 3—3 of Fig. 1.

In the accompanying drawings, I have 50 illustrated a radiator comprising upper and lower longitudinal tubes 1 and 2, a number of upright tubes 3 establishing communication between the tubes 1 and 2 and entering the sides of said last mentioned tubes as is usual with devices of this character. The lower tube 2 is provided at one end with a

combined steam inlet and outlet 4 with which the feed and return pipes, from the boiler to the radiator, may be connected in any suitable manner.

60 The lower side of the tube 2, adjacent the inlet 4, is provided with a downwardly bulged portion 5 which constitutes a continuation of the endmost tubes 3' at this end of the radiator. This downwardly bulged portion constitutes a water trap as will be hereinafter more clearly set forth. Extending across the water trap 5 and joined to the tube 2 and to portions of the tubes 3', at its edges, is a transverse partition 6 which is 65 spaced from the lower end of the trap 5 and which is so disposed as to obstruct communication from the upper portion of the tube 2 and the interior of the upright tubes 3'. The tube 2 is further provided, inside of 70 the partition 6, with an upwardly bulged portion 7 which constitutes an air pocket, said air pocket having an upright discharge opening or vent 8 which communicates with the interior of a discharge pipe 9, the latter 75 having its inner end bent downwardly and engaged with the enlarged outer end of the vent 8 while its outer end extends upwardly. When the parts are properly arranged, the pipe 9 extends longitudinally between the 80 endmost tubes 3' and has its upwardly extending portion spaced a suitable distance 85 from this end of the radiator.

The operation of the invention is as follows: Steam under pressure, is admitted 90 through the nipple 4 and rises through the tubes 3' into the longitudinal tube 1 from which it gradually descends through the various tubes 3, as it cools and discharges into the return tube 2 at the bottom of the 95 radiator. The air in the radiator, being heavier than the steam, will drop through the various tubes 3 and enter the tube 2, the returning steam forcing the air into the pocket 7 from which it is discharged through the vent 8 and pipe 9. As the steam cools, the water of condensation flows into the trap 5 and forms a liquid seal which prevents any air from returning through the 100 nipple 4. As the level of water within the tube 2 rises, the water within the trap 5 will of course likewise rise thus discharging through the nipple 4 and returning to the boiler in a well known manner. If the 105 steam pressure employed is greater than the atmospheric pressure, the air from the interior of the radiator will be freely forced

through the vent 8 and thus discharged. If however, the steam employed in the system, is below the normal atmospheric pressure, it becomes necessary to connect the outer 5 ends of the pipes 9, on the various radiators, with a vacuum system, the operation of these systems being too well understood to require a more extended explanation.

From the foregoing description, taken in 10 connection with the accompanying drawings, it will be seen that I have produced an extremely simple radiator yet one which will be highly efficient in operation and which will effectually discharge any air from its 15 interior thereby causing the steam to exert its greatest amount of energy.

Although in the foregoing description I have described certain elements as best adapted to perform the functions set forth, 20 nevertheless, it is to be understood that various minor changes as to form, material, etc., may be resorted to within the scope of the appended claim without departing from or sacrificing any of the principles of 25 this invention.

Having thus described my invention, what I claim as new and desire to secure by Letters Patent is:

A trap for a radiator comprising a horizontal tube, the lower surface thereof adjacent one end being transversely dished to

produce a relatively wide cup-shaped liquid receptacle, a partition U-shaped in horizontal section integrally formed with and depending from the upper surface of said horizontal tube and having its lower end projecting into the dished portion of said tube and spaced from the bottom thereof, whereby said tube is divided into two compartments, the flanges of said partition forming 35 substantially, continuations of side walls of the narrow portion of said tube, one of said compartments having therein a combined steam and water inlet, said inlet opening into said compartment at a point immediately above the liquid level of the dished portion of said tube, the other compartment of said tube having therein a plurality of steam inlets, said last referred to compartment of said tube also having its upper surface formed with an opening, a flange surrounding said opening and forming a seat, and an air vent having one end disposed in said seat substantially as and for the purpose set forth.

In testimony whereof I have hereunto set my hand in presence of two subscribing witnesses.

JESSE P. WILLIAMS.
